UNITED STATES PATENT OFFICE.

EDWARD FLINT, JR., OF CAMBRIDGE, ASSIGNOR OF ONE-HALF TO CHARLES F. BROWN, OF READING, AND ARTHUR W. CROSSLEY, OF BOSTON, MASSACHUSETTS.

WORK-HOLDER FOR VARIETY MOLDING-MACHINES.

SPECIFICATION forming part of Letters Patent No. 469,938, dated March 1, 1892.

Application filed November 12, 1890. Serial No. 371,185. (No model.)

To all whom it may concern:

Be it known that I, EDWARD FLINT, Jr., of Cambridge, in the county of Middlesex and State of Massachusetts, have invented certain new and useful Improvements in Work-Holders for Variety Molding-Machines, of which the following is a specification.

This invention has for its object to provide a simple and effective device whereby the operator of a variety molding-machine can present a piece of work to the cutter-head of the machine, move the work horizontally on the table of the machine to pass the work across the cutter-head and cause the cutter-head to make a longitudinal groove in the work, partly turn the work after each pass of the same across the cutter, and secure it so that during the next pass another groove will be made having a predetermined relation to the last groove, until the entire surface of the work has been ornamented by a series of grooves, all separated by spaces of uniform shape, the invention being intended to aid an operator in making longitudinal flutings on cylindrical and other shaped pieces for use as legs, posts, &c., on furniture, or diverging flutings or ribs on flat pieces to be used as medallions to ornament mantels, furniture, &c.

The invention consists as a whole in a work-holder comprising a base-plate adapted to be moved freely about on the table of a variety molding-machine by the operator, two vertical standards mounted on said base and adjusted both lengthwise and crosswise thereon, a work-engaging center mounted to rotate in a bearing on one of said standards, an index-wheel affixed to said center so as to rotate therewith, a latch attached to said standard and adapted to engage the index-wheel and hold the same in various positions, and another center attached to the other standard and adapted to co-operate with the said rotary center in supporting a piece of work to be ornamented.

The invention also consists in certain other improvements, all of which I will now proceed to describe and claim.

In the accompanying drawings, forming a part of this specification, Figure 1 represents a perspective view of a work-holder embody-

ing my invention. Fig. 2 represents a top view of the same. Fig. 3 represents a horizontal section through the index-wheel and the standard supporting the same. Figs. 4 and 5 represent views of auxiliary devices used with my improved work-holder. Fig. 4^a represents a side view of the index-wheel and its supporting-standard separated from the supporting-base and secured to the device shown in Fig. 4 as a means for making radial grooves in a flat piece or rosette. Figs. 6 and 7 represent side views of pieces of work as ornamented by the aid of my improved holder.

The same letters and numerals of reference indicate the same parts in all the figures.

In the drawings, *a* represents a flat base-plate, adapted to be moved freely about on the table *b* of a variety molding-machine.

c c' represent slides, which are engaged with shoulders *a' a'* on the plate *a*, said shoulders being preferably inclined or dovetailed, the slides being adjustable lengthwise of the base-plate and adapted to be secured in any position to which they may be moved by set-screws *d d*.

e e' represent standards attached, respectively, to the slides *c c'* by screws *f f'*, passing through slots *g g'* in flanges formed on said standards and bearing on the slides, the standards being thus made adjustable crosswise of the base. To the standard *e* is secured by bolts *h h*, Fig. 3, a block or slide *i*, the rear side of which is recessed at *i'* to receive a nut *j* on the end of a bolt *k*, which is formed on a stud or center *l*. Said center *l* and its bolt *k* are adapted to rotate, the bolt turning freely in a bearing formed for it in the slide *i*. The outer end of the center is provided with spurs *l' l'*, which enable it to engage one end of the piece of work *m*, so that said piece and the center necessarily rotate together, the other end of the piece being supported by a pointed stud or center *n* on the standard *e'*, said center *n* permitting the work to rotate freely.

o represents an index-wheel, which is so connected with the center *l* that it rotates therewith, and is provided with several concentric rows or series of holes *o'*, each row having a different number of holes. A spring-latch *p*, 100

having a pin p' , Fig. 2, is supported by an arm q on the slide i in such manner that said pin may be inserted in a hole of any row in the index-wheel when such hole is brought 5 into coincidence with the pin by the rotation of the index-wheel, the latch being connected with the arm q by a screw r , so that its end that carries the pin may swing toward and from the axis of the index-wheel, and therefore 10 fore assume any position required to enter a hole in any row. The slide i , supporting the center l and index-wheel o , is vertically adjustable by means of vertical slots $s s$ in the standard e , the bolts $h h$ passing through said 15 slots. The center n is a screw passing through a plate or slide t , which is attached by bolts $u u$ to the standard e' , said plate being vertically adjustable by slots $v v$ in said standards, through which the bolts $u u$ pass. Another 20 slot v' in the standard e' permits the necessary vertical movement of the center n when the plate t is vertically adjusted, the center passing through the slot v' . The center n has a hand-wheel n' to enable it to be conveniently 25 adjusted endwise by rotation in securing and releasing the work.

In operating the above-described device when the work is circular in cross-section, like a table-leg, Fig. 6, or other like form, and 30 is to be grooved or fluted lengthwise, the work is secured between the centers $l n$, the endwise adjustment of the center n pressing the work firmly onto the spurs of the center l , so that said center and the index-wheel are engaged with the work and necessarily rotate therewith. The work being locked in the desired position by the engagement of the latch-pin p' with a hole in the index-wheel and the base-plate resting on the table of a variety 35 of molding-machine, the operator, grasping the base-plate, moves the same first to bring the work in contact with the cutter-head 10 (shown in dotted lines in Fig. 2) and then to cause the work to move endwise while in contact with said cutter-head, the result being 40 the formation of a longitudinal groove 7, Fig. 6, in the work, said groove being the first of a series. The work is then turned one step, the pin p' being withdrawn from the index-wheel to permit the partial rotation of the work, and then engaged with another hole to again lock the work, and the above-described 45 movements of the work-holder are repeated, thus forming another longitudinal groove 7, and so on until the entire periphery of the 50 piece of work is ornamented. The width of the spaces between the grooves thus formed is determined by the holes of the index-plate, the form of the grooves being, of course, determined by the form of the cutter.

In case it is desired to form a series of radial grooves 8 in a flat piece 9, such as is shown in Fig. 7, the standard e' and center n are dispensed with and the slide c is removed from the base a , said slide then constituting a base, which supports the standard e and index-wheel o , as shown in Fig. 4^a. The

center l is removed and a plate 12, Fig. 4, is secured to the index-wheel in place of said center, said plate having a flat outer face and a screw stud or spur 13, projecting outwardly from said face. The piece of work 9 is attached to the plate 12 by means of said screw-stud, which enters the back of the piece. The operator locks the piece 9 in a series of positions by means of the index-wheel and latch, and after each locking moves the holder while pressing the work against the cutter-head, the result being the formation of the radial grooves 8, Fig. 7. It will be seen that in either case 80 the work may be securely held in a variety of positions and presented while in any of said positions to the cutter-head.

When the machine is used as a whole, the adjustability of the standards $e e'$ on the 85 slides $c c'$, afforded by the slots $g g'$ and screws $f f'$, enables the centers $l n$ to be adjusted laterally to adjust the center of gravity of the work and prevent the holder from tipping over when the work is of such form that its center 90 of gravity is at one side of the center of gravity of the work-holder. The vertical adjustability of the centers $l n$, afforded by the slots $v v s s$, slides $i t$, and bolts $h h$ and $u u$, enable the centers to be adapted to the thickness or 95 height of the work, while the independent adjustability of the standards $e e'$ lengthwise of the base a enable the centers to be adapted to the length of the work.

When long and slender pieces of work are 100 being ornamented, I employ as a support to prevent the springing of the work at its central portion an ear or bracket 15, Fig. 5, having dovetail lugs 16 16, adapted to engage the shoulders $a' a'$ of the base a . Said bracket 105 is secured to the base about midway between the standards $e e'$ and its upper end supports the central portion of the work either by bearing directly against the latter or by holding a piece of wood or other material against the 110 under side of the work, said piece being secured firmly to the bracket 15 by means of a screw 17 thereon.

When the index-wheel and its supporting devices are used, as shown in Fig. 4^a, the plate 115 12 and its screw stud or spur 13 become the equivalent of the centers $l n$ in holding the work in engagement with the index-wheel.

It is obvious that when vertical adjustability is not an object the center l and index-wheel may be mounted directly on the standard e and the center n on the standard e' .

I claim—

1. The combination of the base-plate, the slides $c c'$, adjustably connected with said base-plate, the standards $e e'$, affixed to said slides, the slides $i t$, vertically adjustable on the standards $e e'$, the center l , index-wheel o , and latch p , supported by the slide i , the screw-threaded center n , supported by the slide t , and means for securing the slides $i t$ to the standards $e e'$ at any position to which they may be adjusted, as set forth.

2. The combination of the base-plate, the

standards $e e'$, supported thereby and provided with vertical slots, the slides $i t$, mounted on said standards and provided with attaching-bolts passing through the slots in said standards, the center l , index-wheel o , and latch p , supported by the standard e , supported by the slide i , and the center n , supported by the slide t , as set forth.

5 3. The combination of the base-plate, the slides $c c'$, adjustable thereon, the standards $e e'$, provided with base-flanges having slots extending crosswise of the base-plate, screws passing through said slots and securing the said flanges to the slides $c c'$, said slots and

screws permitting the lateral adjustment of the said standards, the center l , index-wheel o , and latch p , supported by the standard e , and the center n , supported by the standard e' , as set forth.

In testimony whereof I have signed my name to this specification, in the presence of 20 two subscribing witnesses, this 6th day of November, A. D. 1890.

EDWARD FLINT, JR.
